UNITED STATES PATENT OFFICE

HOWARD D. MCLEOD, OF GREAT FALLS, MONTANA.

ORE-CONCENTRATING TABLE.

No. 850,391.

Specification of Letters Patent.

Patented April 16, 1907.

Application filed February 8, 1905. Serial No. 244,723.

To all whom it may concern:

Be it known that I, HOWARD D. MCLEOD, a citizen of the United States, residing at Great Falls, in the county of Cascade and 5 State of Montana, have invented certain new and useful Improvements in Ore-Concentrating Tables, of which the following is a specification.

My invention relates to improvements in 10 the class of ore-concentrators known as the "Rittinger type," where the feed is introduced at the end of one side of a nearly-horizontal table or plane and is concentrated under the influence of a horizontal vibration 15 and the cross-wash of water, so that the values being separated out by gravity may be conducted in one direction and saved, while the gangue is discharged in another direction, being carried away by the washing-water. 20 My invention comprises a plurality of tables or planes one placed directly above the other and acting in series on the same mass of material and of novel means for supporting said planes and for giving them the requisite vibratory motion. 25

It further consists of details of construction, which will appear in the description of the device.

Figure 1 is a top plan view of an ore-concentrating device embodying my invention. Figs. 2 and 3 are front and end elevations of the device. Fig. 4 is a partial perspective view of the table, its position being the reverse of that shown in Fig. 1.

35 1 designates a deck or table used for the roughing out or preliminary classification of material to be treated. It is of smaller size than the main table 2 and may be supported in any desired manner so that it occupies a 40 position immediately above the head end of the main table. It is preferably directly mounted on the main table, so as to share the horizontal vibration of the latter. I have shown it as detachably supported by means 45 of a vertically-adjustable leg 11 at its feed side and a rod 12, pivotally mounted in brackets 13, at its discharge side. This preliminary deck or table 1 is preferably provided with the usual longitudinal riffles 14 and 50 feed-box 15. At its tail end it has a launder 16, discharging into the usual launder on the main table 2. At the head end of the discharge side of the deck 1 is an inclined laun-

der 17, while the tail end of this side has a projecting apron 18, these parts being clearly 55 shown in Fig. 4.

I prefer to extend the riffles 14 and 25, as shown, to the extreme end of the deck or table 1 and of the main table 2. This arrangement maintains the stratification, so 60 that when values of different specific gravities occur they may be easily caught in different receptacles. The operation of this portion of my invention has already been indicated. It is clear that the pulp feed from the pipe 3 65 into the feed-distributing box 15 is spread over the feed side of the deck 1. By means of the adjustable leg 11 the inclination of the deck may be arranged as desired. It is also clear that under the longitudinal vibration of 70 the deck the coarser values or enriched minerals will work their way into the transverse launder 16 and will be washed by the spray from the pipe 31 into the main launder 26 of the table 2. At the same time the gangue 75 and the coarser of the remaining metals will pass to the tail end of the deck over the apron 18 and into the main feed-box 23 at the head of the table 1, while the slime and lighter portions will be discharged by the inclined launder 17 into the feed-box 24, thence to the table 1 in advance of the relatively coarse portions. The further movement of the material and the complete separation of the 80 values from the gangue is accomplished in 85 the usual manner.

Figs. 2 and 3 of the drawings show my novel means for producing the desired longitudinal vibration of the table 2, while efficiently preventing the trembling or vertical 90 vibration which is so destructive to perfect separation. As shown, the table 2 is supported on a plurality of legs 4, pivotally attached at their upper ends to lugs 41 on the table and at their lower ends to similar lugs 95 42 on a frame 5, which obviously may be any part of the building, but which, as shown, is a separate frame and is firmly bolted to the floor of the building. I have shown each leg 4 as composed of two lengths of rod threaded 100 at their adjacent ends and united by a turn-buckle 43, by means of which the length of each leg may be separately and accurately adjusted, and the leg may be maintained either in tension or in compression. The 105 range of legs 4 at one side of the table 2—as

shown the feed side—is secured to the frame through bell-crank levers 51, pivoted to the frame at their elbows, their upper arms being all pivoted to a horizontal rod 52. Any desired means (not shown) may be employed to longitudinally adjust the rod 52 and to maintain it in its adjusted position. It is plain that the transverse inclination or tilt of the table 2 may be in this way altered as desired 10 by a single operation and without buckling or distorting it. Transverse braces 53 (shown in Fig. 3) may be employed to prevent racking of the legs 4.

A connecting rod or link 6 extends from the table 2 to any desired means for producing rapid vibration. I have shown the preferred means to this end in my pending application, Serial No. 215,725, filed July 8, 1904; but any well-known vibrating engine 20 may be employed. To prevent strain on the table, I preferably carry beneath it a rod 61, pivotally attached at one end to the link 6, passing through and firmly secured to each of several cross beams or ribs 27 on the lower 25 side of the table 2 and to a cross-bar 62 at the lower end of the table. To the cross-bar 62 is pivoted one end of the lever 63, journaled on a rod 64, which is mounted in brackets 54 on the frame 5. A spring 65 connects the 30 lower end of the lever 63 to a stationary part of the frame 5 and tends to maintain the table 2 at one end of its path of vibration.

Among the advantages of my device may be noted the saving of floor-space by a series 35 of vibratory classifying-tables one directly above the other, operating successively or "in series" on the same mass of material; economy of operation caused by the discharge of the classified material from the 40 deck to the main table in their inverse order—*i. e.*, with the heavier materials near the head end of the table; simplicity, gained by connecting the two or more classifying-tables to move in unison; absolute smoothness of vibration, due to the tying down of 45 the table at several points to a solid frame, whereby vertical movement is eliminated; individual adjustability of each leg or support by which any buckling on the table may 50 be corrected; simultaneous and equal adjustment of the transverse inclination of the table, and ease of making these various 55 adjustments, which can, indeed, be made without stopping the movement of the table.

It is obvious that certain parts of my device may be advantageously employed without the others, that the number of tables to be superimposed is not limited except by the requirements in each case, and that many 60 other alterations may be made in the device without departing from my invention.

Having thus described my invention, and without limiting myself to the construction shown and described nor enumerating equiv-

alents, what I claim as new therein, and desire to secure by Letters Patent, is—

1. An ore-concentrating device comprising a vibratory table, a stationary rigid frame beneath said vibratory table, a plurality of inflexible bodily-adjustable supports positively secured both to said table and to said frame for resisting both tensile and compressive strains, and means for simultaneously and equally adjusting said supports bodily, whereby the distance between said table and said frame may be altered.

2. An ore-concentrating device comprising a vibratory table, a plurality of separately, longitudinally bodily adjustable inflexible supports at one side of said table, a stationary rigid frame beneath said table, and operative connections between the upper ends of said supports and said table and between the lower ends of said supports and said frame for maintaining said supports either in tension or in compression.

3. An ore-concentrating device comprising a vibratory table, a stationary rigid frame beneath said table, a plurality of series of separately, longitudinally bodily adjustable inflexible supports between said table and said frame for resisting both tensile and compressive strains, and means for vertically and bodily adjusting one side of said table through one series of said supports, independently of the other series, said adjusting means being operative while the table is in vibration.

4. An ore-concentrating device comprising a table, a stationary rigid frame beneath said table, a series of adjustable inflexible supports at each side of said frame and extending to said table, said supports being pivotally attached both to said frame and to said table, for resisting both tensile and compressive strains, and means for simultaneously and equally adjusting the length of all of the supports in one of said series.

5. An ore-concentrating device comprising a table, a stationary rigid frame beneath said table, a series of inflexible supports at each side of said frame and extending to said table, said supports being pivotally attached both to said frame and to said table for resisting both tensile and compressive strains, means for simultaneously and bodily adjusting the length of the supports in one of said series, and independent means for separately adjusting the length of each of the supports in said series.

6. An ore-concentrating device comprising a table, a stationary rigid frame beneath said table, a series of inflexible supports at each side of said frame and extending to said table, said supports being pivotally attached both to said frame and to said table for resisting both tensile and compressive strains, each of the supports of one of said series be-

ing composed of two inflexible threaded portions united by a turnbuckle.

7. An ore-concentrating device comprising a table, a stationary rigid frame beneath said table, a series of inflexible supports at each side of said frame and extending to said table, said supports being pivotally attached both to said frame and to said table for resisting both tensile and compressive strains and also for resisting lateral movement of said table, and pivoted braces between said table and said frame for additionally resisting lateral movement of the table.

8. An ore-concentrating device comprising a table, a stationary rigid frame beneath said table, a series of inflexible supports at each side of said frame and extending to said table, said supports being pivotally attached both to said frame and to said table for resisting both tensile and compressive strains, and transverse braces pivoted to said frame and secured to said supports adjacent to their upper ends for additionally resisting lateral movement of the table.

25 9. An ore-concentrating device comprising a vibratory table, a stationary rigid frame beneath said table, a series of inflexible supports at each side of said table and extending to said frame for resisting both tensile and compressive strains, said supports being so transversely pivoted to one of said parts as to permit longitudinal vibration, and so pivoted to the other of said parts as to permit longitudinal vibration and lateral adjustment of the table, the series of supports at one side of said table being longitudinally adjustable, for the purpose specified.

10. An ore-concentrating device comprising a vibratory table, a stationary rigid frame beneath said table, a series of inflexible supports at each side of said table and extending to said frame for resisting both tensile and compressive strains, said supports being so transversely pivoted to said frame as to permit longitudinal vibration, and so pivoted to said table as to permit longitudinal vibration and lateral adjustment of the table, the series of supports at one side of said table being longitudinally adjustable, for the purposes specified.

11. An ore-concentrating device comprising a vibratory table, a stationary rigid frame beneath said table, a series of inflexible supports at each side of said table, and extending to said frame, said supports being so transversely pivoted to one of said parts as to permit longitudinal vibration and so pivoted to the other of said parts as to permit longitudinal vibration and lateral adjustment of the table, said supports being positively attached both to said frame and said table to resist both tensile and compressive strains, for the purposes specified.

12. An ore-concentrating device comprising

ing a vibratory table, a stationary rigid frame beneath said table, a series of inflexible supports at each side of said table and extending to said frame, said supports being so transversely pivoted to said frame as to permit longitudinal vibration and so pivoted to said table as to permit longitudinal vibration and lateral adjustment of the table, said supports being positively attached both to said frame and said table to resist both tensile and compressive strains, the series of supports at one side of said table being longitudinally adjustable, for the purposes specified.

13. An ore-concentrating device comprising a vibratory table, a stationary rigid frame beneath said table and a series of inflexible supports at each side of said table for resisting both tensile and compressive strains and comprising legs so transversely pivoted to one of said parts as to permit longitudinal vibration, and lugs transversely pivoted to said legs and longitudinally pivoted to the other of said parts, the series of supports at one side of said table being longitudinally adjustable, whereby the lateral inclination of the table may be adjusted, for the purposes specified.

14. An ore-concentrating device comprising a vibratory table, a stationary rigid frame beneath said table, a series of inflexible supports at each side of said table and extending to said frame for resisting both tensile and compressive strains, said supports being so transversely pivoted to one of said parts as to permit longitudinal vibration, and so pivoted to the other of said parts as to permit longitudinal vibration and lateral adjustment of the table, and means for simultaneously and equally adjusting the length of the supports in one of said series, for the purposes set forth.

15. An ore-concentrating device comprising a vibratory table, a stationary rigid frame beneath said table, a series of inflexible supports at each side of said table and extending to said frame for resisting both tensile and compressive strains, said supports being so transversely pivoted to one of said parts as to permit longitudinal vibration and so pivoted to the other of said parts as to permit longitudinal vibration and lateral adjustment of the table, means for simultaneously and equally adjusting the length of the supports in one of said series, and means for separately adjusting the length of each of the supports in said series, for the purposes set forth.

16. An ore-concentrating device comprising a vibratory table, a stationary rigid frame beneath said table, a series of inflexible supports at each side of said table for resisting both tensile and compressive strains and comprising legs so transversely pivoted to one of said parts as to permit longitudinal

vibration and lugs transversely pivoted to said legs and longitudinally pivoted to the other of said parts, each of the legs in one of said series being composed of two threaded portions united by a turnbuckle, for the purposes set forth.

In testimony whereof I have signed this

specification in the presence of two subscribing witnesses.

HOWARD D. MCLEOD.
